UNITED STATES PATENT OFFICE.

GEORGE H. GIFFIN, OF TOPEKA, KANSAS.

TRAP-DOOR HINGE FOR RAILWAY-COACH VESTIBULES.

SPECIFICATION forming part of Letters Patent No. 727,933, dated May 12, 1903.

Application filed February 2, 1903. Serial No. 141,456. (No model.)

To all whom it may concern:

Be it known that I, GEORGE H. GIFFIN, a citizen of the United States of America, residing at Topeka, in the county of Shawnee and State of Kansas, have invented new and useful Improvements in Trap-Door Hinges for Railway-Coach Vestibules, of which the following is a specification.

The invention has special reference to the newer construction of railway-coach vestibules, in which the sides and side doors of the vestibules are approximately on a line with the sides of the coach, the area of the steps being covered by a trap-door which when the side door of the vestibule is to be opened to permit ingress or egress by way of the car-steps is folded back of the vestibule-door and against the end of the coach.

It is the object of the invention to provide a hinge for the trap-door which is simple and economic in construction, which is strong and not readily broken or liable to be torn from its seat, and which permits the trap-door to be folded snugly against the end of the coach and also forms a safe support for the door. Although more especially designed for use on trap-doors for vestibules, it will be apparent that it will prove equally desirable in other similar constructions where like objects are to be accomplished.

The invention consists of the novel combination, arrangement, and disposition of the parts, the preferred form of the embodiment whereof is herein described and claimed and is shown in the accompanying drawings, forming part of this specification.

Figure 1 is a top or plan view of the strap member. Fig. 2 is a side view thereof. Fig. 3 is a cross-section through the line 3-3 of Figs. 1 and 2. Fig. 4 is a front view of the abutting plate or stationary member, with a dotted outline of a portion of the trap-door and strap member thereto attached in the position, horizontal, shown in Fig. 5, which is a section through the line 5-5, Figs. 4, 1, and 3, and which shows the hinge attached to the trap-door, with a portion of the coach end to which the abutting member is fitted.

Like letters of reference indicate like parts throughout the several views.

The invention is a loose-joint butt-and-strap hinge.

C is the strap member, having a knuckle E and the integral plate F, whose ends *ff* project from the sides of the knuckle. H is the butt member, having an opening G and slots *gg* extending laterally from the upper end thereof to accommodate, respectively, said knuckle and said plate F and projecting ends *ff*.

I is a lug protruding from the plate H to form a supporting-bracket for the trap-door B in order that the strain shall not all be on the strap C.

A represents a section of the framework of the coach end, A' being a recess chiseled out to accommodate the knuckle E, and B represents a section of the trap-door.

B' C' E' F' represent the position of the trap-door and strap member when the trap-door is folded up against the coach end.

D and *hh* are suitable screw-holes.

The construction and proportion of the parts comprising the hinge are such that when the same are assembled, as shown in Fig. 5, the plate on the knuckle E, having the projecting pins *ff*, bears against the inner face of the plate H, while the trap-door secured to the inner face of the strap C abuts snugly against the outer face of said plate and is supported by the lug I, projecting from said plate H.

The plate H may be countersunk into the coach end, and a recess is chiseled out behind it to make room for the pin and knuckle. The strap or movable member C is screwed to the under side of the trap-door, the knuckle abutting the edge of the door. It is understood, of course, that there are ordinarily to be a pair on each door. The hinge is connected together or interlocked by holding the door in a vertical position, raising the knuckle E above the support I until the projections *ff* register with the slots *gg*, when they (the projections and knuckle) are pushed through the plate H, and the door, still held vertically, is lowered until the knuckle E rests on the support I, as shown by the dotted outline B' C' F', Fig. 5. The door may be held in this position by any suitable means, as by a hasp, (not here shown,) when the steps are in use. The door swings on the knuckle E, which bears on the lower side of the opening G and on the support I and is held snugly up against

the end of the coach by the pin F and projections *f f*.

The plate F and projections *f f* are wider than the slots *g g*, so as to form a closure for 5 said slots, thus preventing dirt from getting in and clogging the parts.

There may be slight variations from the exact description shown herein and in the drawings without departing from the spirit of the 10 invention.

What I claim as new, and desire to secure by Letters Patent, is—

In a trap-door hinge the combination with

the strap C provided with the knuckle E having the plate F and pins *f f* projecting laterally from said plate, of an abutting plate H having an opening G and slots *g g*, whereby the strap C may be operatively connected to the abutting plate and be supported thereby. 15

In testimony whereof I have affixed my signature in presence of two witnesses.

GEORGE H. GIFFIN.
